CHIMES

Filed July 12, 1929

Fig. 1.

Inventor

By Robert Robb Attorneys

UNITED STATES PATENT OFFICE

THOMAS J. BRIMER, OF CHICAGO, ILLINOIS, ASSIGNOR TO GOOD HUMOR CORPORATION OF AMERICA, OF CLEVELAND, OHIO, A CORPORATION

CHIMES

Application filed July 12, 1929. Serial No. 377,879.

In the vending of commodities throughout a community from an automobile or similar vehicle, it is highly desirable to have some sort of a signal to announce the approach 5 of the same.

The object of my invention, therefore, has been to devise a novel mechanism which may be associated with the vehicle to announce its presence in the vicinity.

10 To be more specific, I provide chime means mounted upon a novel hanger which in turn is suspended from the body of the vehicle. The hanger is suspended in such a manner that it is rocked as the vehicle encounters 15 rough spots in the road or by a change in acceleration of the vehicle and also I provide a pull arm whereby the hanger may be manually operable.

The hanger member preferably comprises 20 a horizontal bar and hanger members upturned at the ends thereof and which are provided with apertures therethrough. The suspension means is preferably secured to the body of the vehicle and is formed with 25 laterally extending portions which pass through the openings in the hangers so that the device is adapted to rock about a horizontal axis disposed at right angles to the path of travel of the vehicle.

30 Various other and more detailed objects will appear as the description of the invention proceeds.

For a full and more complete understanding of the invention, reference may be had 35 to the following description and accompanying drawings, in which—

Figure 1 is a side elevation of a portion of a vehicle body having my novel device affixed thereto.

40 Figure 2 is a side view of the device.

Figure 3 is a bottom view of the same.

Figure 4 is a detail view of the supporting member and clappers associated therewith.

Throughout the following description and 45 accompanying drawings, like reference characters denote corresponding parts.

While a preferred, specific embodiment of the invention is herein set forth, it is to be understood that I am not to be limited to the exact constructions illustrated and de-

scribed, because various modifications of these details may be provided in putting the invention into practice within the purview of the appended claim.

A vehicle body with which my novel device is associated is generally denoted at A. The device comprises a horizontal bar 1 having upturned end portions or hangers 2. The hangers 2 are apertured at 3 for reasons to be hereinafter set forth. A plurality of 55 bells 4 are secured to the hanger member by any suitable means such as the rivets 5. In the preferred form, the bells 4 are each of a different size so as to give off sounds of different pitches.

In the present instance I have shown four 60 bells secured to the horizontal bar 1. Each bell is provided with three clappers. The clappers comprise weights 6 freely suspended by means of wires 7. The three wires for 65 each bell are freely fastened to a supporting member 8 which is secured to the corresponding bell and horizontal bar by the rivet 5 which also secures the bell to the bar.

The vehicle body A is provided with suspension means which in the present embodiment include a vertical screw threaded portion 9 and a lateral outstanding portion 10 which is disposed in a horizontal plane, the lateral portions 10 passing through the apertures 3 of the hangers 2 so that the device as 70 a whole may be rocked about the suspension means.

I prefer to locate my device so that the horizontal bar 1 is at right angles to the path 75 of travel of the vehicle. It can thus be readily seen that as the vehicle travels over the road the device will be rocked by changes in motion of the vehicle or by the vehicle passing over uneven spots in the road. For manual control of the device I provide a pull 80 arm 11 secured to the bar 1 by means of a rivet 12. The pull arm is of angular formation, one part being disposed parallel to the road and the other part being perpendicular 85 thereto. At the end of the perpendicular part of the pull arm there is a hole 13 for receiving a flexible wire 14 which in turn passes through a hole 15 in the body of the vehicle.

The free end of the flexible wire 14 is pro- 90 95 100

vided with a knob 16 to facilitate the operation thereof. A pulley 17 may also be secured to the body of the vehicle and the flexible wire 14 threaded thereover.

Because of the novel mounting of my device as has been hereinbefore pointed out, the chimes comprising the bells and clappers will ring under the slightest movement of the vehicle and by means of the pull arm and parts associated therewith the chimes may be manually operated either while the vehicle is moving or when it is standing still.

Having thus described my invention, what I claim as new and desire to secure by Letters Patent of the United States, is—

In a vehicle from which edibles are vended, means for audibly attracting the attention of the public, said means comprising a bar having a body and ends bent at right angles to the body, said ends having openings, pivot elements disposed in said openings and having means for attachment to a vehicle, whereby said bar may be pivotally suspended, a plurality of spaced chime members, a plurality of spaced hammers pivotally attached to each chime member, and means common to each chime member and its hammers for fixedly securing them to said body, whereby any movement of said body about said pivots results in operation of said chimes.

In testimony whereof I affix my signature.
THOMAS J. BRIMER.
